[57] CLAIM

The ornamental design for a physical exerciser, as
shown and described.

DESCRIPTION

FIG. 1 is a perspective view of a physical exerciser
showing my new design;

FIG. 2 is a side elevational view opposite to that shown
in FIG. 1;

FIG. 3 is a bottom plan view thereof;

FIG. 4 is a left end elevational view thereof; and,

FIG. 5 is a right end elevational view thereof.

FIG 1

FIG 2

FIG 3

FIG 5
